UNITED STATES PATENT OFFICE.

IRVING W. RICE, OF NEW YORK, N. Y.

DESIGN FOR A DISPLAY-CASE.

59,871.

Specification for Design.

Patented Nov. 29, 1921.

Application filed December 5, 1919. Serial No. 342,842. Term of patent 7 years.

To all whom it may concern:

Be it known that I, IRVING W. RICE, a citizen of the United States, and a resident of New York, county and State of New York, have invented a new, original, and ornamental Design for Display-Cases, of which the following is a specification, reference being had to the accompanying drawings, forming a part thereof, in which—

Figure 1 is a plan view of a display case showing my new design and Fig. 2 is a cross-section thereof on the line 2—2 of Fig. 1.

My invention relates more particularly to display cases for manicure implements and accessories.

Referring to the drawings, it will be seen that my ornamental display case is rectangular in shape, and provided with a plurality of vertically and horizontally disposed compartments. Two of the vertically

disposed compartments, while being of substantially the same width as those at the right thereof are longer by the width of the transverse compartment. The compartments to the left of the longer vertical compartments are wider than those to the right, and a transverse partition divides one of the wide spaces into two compartments. The display case is covered by a single plate of glass of a size to overhang the walls of the case uniformly, on all sides. Numbers which may indicate the price of the articles in the respective compartments are preferably placed on the cover glass, over each compartment.

I claim:

The ornamental design for a display case as shown.

IRVING W. RICE.
